UNITED STATES PATENT OFFICE.

JOHN ANSON BUCK, OF BROOKLYN, NEW YORK.

DESIGN FOR A PAD FOR HORSESHOES.

SPECIFICATION forming part of Design No. 34,692, dated June 25, 1901.

Application filed April 4, 1901. Serial No. 54,392. Term of patent 7 years.

To all whom it may concern:

Be it known that I, JOHN ANSON BUCK, a citizen of the United States, residing at Brooklyn, in the county of Kings and State of New York, have invented and produced a new and original Design for Horseshoe-Pads, of which the following is a specification, reference being had to the accompanying drawings, forming part thereof, in which—

10 Figure 1 is a bottom plan view of my newly-designed pad for horseshoes, and Fig. 2 a transverse section thereof on the line $x-x$ of Fig. 1.

15 The leading or material feature of my newly-designed pad for horseshoes consists in the general form thereof, which is that of a horseshoe, the side portions a , however, being thickened transversely at the heel portions thereof, as shown at b , and the transverse thickness of the front portion of the pad and the front side portions being substantially the same. As shown in the drawings, the bottom

or bearing surface of the pad is roughened or corrugated, as shown at c , and is also provided with grooves d at the rear ends of the 25 separate sides, which are arranged approximately near the outer edges of the rear end portions of said sides and which converge forwardly and meet at d' , from which point a single groove e extends around the front side 30 portions and also the front portion of the pad.

Having fully described my invention, what I claim as new, and desire to secure by Letters Patent, is—

35 The design for a pad for a horseshoe herein shown and described.

In testimony that I claim the foregoing as my invention I have signed my name, in presence of the subscribing witnesses, this 3d day of April, 1901.

JOHN ANSON BUCK.
